UNITED STATES PATENT OFFICE.

JOHN SALM, OF TORRANCE, CALIFORNIA.

DESIGN FOR A BACK OF A MIRROR, HAIR BRUSH, OR SIMILAR ARTICLE.

Application filed December 16, 1920. Serial No. 431,260. Term of patent 3½ years.

To all whom it may concern:

Be it known that I, JOHN SALM, a citizen of the United States, residing at Torrance, in the county of Los Angeles and State of California, have invented a new, original, and ornamental Design for a Back of a Mirror, Hair Brush, or Similar Article, of which the following is a specification, reference being had to the accompanying drawing, forming a part thereof.

The figure is a view of the back of a mirror showing my new design.

The trapezoidal insets in the group are arranged within the rounded border and the trapezoidal inset of the handle is arranged within an ovulate border extension.

I claim.

The ornamental design for a back of a mirror, hair brush or similar article as shown.

Signed at Los Angeles, in the county of Los Angeles and State of California, this 9th day of December, 1920.

JOHN SALM.
